UNITED STATES PATENT OFFICE.

CLARENCE E. STEVENS, OF CLEVELAND, OHIO, ASSIGNOR TO WHITE SEWING MACHINE CORPORATION, OF CLEVELAND, OHIO, A CORPORATION OF DELAWARE.

SEAT CONSTRUCTION.

Application filed February 14, 1927. Serial No. 167,882.

This invention relates to a seat structure and finds special utility in school room seats though it may be used to advantage in seats for other purposes.

5 One of the objects of the present invention is to provide an improved swivel support for the seat on the post which is adapted to support it, the particular object in this connection being to provide a swivel 60 connection between the seat and post composed of parts which have great durability and are inexpensive to construct and assemble.

10 The above objects are attained very effectively by my invention which may be here briefly summarized as consisting in certain novel details of construction, and combinations and arrangements of parts which will be described in the specification and set forth 15 in the appended claims.

15 In the accompanying sheet of drawings, Fig. 1 is a side view of a seat and desk unit, the seat portion of which embodies my invention; Fig. 2 is a vertical sectional view 20 on an enlarged scale showing the support and swivel connection for the seat embodying the invention; Fig. 3 is a top plan view of the seat supporting and swivelling parts which lie directly beneath the seat; and Fig. 25 4 is a transverse sectional view substantially along the line 4—4 of Fig. 2.

30 In Fig. 1, the seat 10 is a part of a unit which includes also the desk 11, the seat and desk being joined by a U-shaped tubular member 12 with upstanding ends which receive, respectively, a seat supporting post 13 and a desk supporting post 14, which posts slidingly engage the ends of the tube and are adapted to be held at any desired 35 height and elevation therein. The lower and horizontal portion of the tube is held slightly above the floor level by legs 15 and 16, which are secured to the upper portions of the tube and project laterally therefrom. 40

45 It should be here stated that my invention is not confined to a seat and desk unit but may be employed equally well in a seat formed as a separate unit.

50 Taking up next the details of the swivel supporting connection between the seat 10 and post 13, there is provided at the top of post 13 a laterally projecting hardened disk 17 which is fixed to the post preferably by providing at the center of the disk a 55 tubular boss or bushing 17^a which is fitted

over the end of the post and is secured thereto in any suitable way, as by a pin 19, by welding, or otherwise. The plane of the disk 17 is preferably slightly inclined with respect to the axis of post 13 so as to coincide with the inclination of the seat 10.

55 On the under side of the seat there is secured a plate 20 having a circular marginal flange 20^a, which is secured to the seat by screws 21 and inside of this flange, the plate 60 has a circular portion 20^b which is offset with respect to the flange away from the seat so as to form an annular pocket which receives the disk 17. At the center of the offset portion 20^b of the plate 20, there is an 65 opening through which the tubular portion 17^a of the disk projects.

70 The weight of the occupant of seat 10 is transmitted to the upper end of the post 13 and the disk 17 and to prevent undue 75 wear between these parts, there is interposed above the post 13 and disk 17 a hardened wear resisting disk 22, this being immediately beneath the seat 10 as illustrated in Fig. 2.

80 It will be observed that the disk 17 is provided with corrugations 17^b so as to reduce the wear resisting surface between the disk 17 and the disk 22 and also between the disk 17 and the offset portion 20^b of the plate 20. 85 Likewise, it will be observed by reference particularly to Fig. 3 that the peripheral portion of the disk 17 is notched out leaving radially disposed lugs 17^c which, in this instance, are three in number and are equally 90 spaced. Two of these lugs 17^c act as stops to limit the swinging movement of the seat in both directions and in order that they may serve this purpose, there is struck up from the offset portion 20^b of plate 20 a lug 95 20^c (note Figs. 2 and 3). While two of the lugs 17^c are all that are required to limit the swivelling movement of the seat, nevertheless the third lug is preferably employed as it provides a balanced construction especially useful when the weight of the occupant is shifted to different portions of the seat and furthermore it centers the seat upon the post.

100 It will be observed that disk 22 is bowed, 105 being curved down so as to engage the corrugations on disk 17. This at all times causes a frictional resistance to the turning movement of the seat in either direction from its central position, thus reducing the 110

liability of a shock or noise by the engagement of the stop lugs when the seat is turned.

Thus it will be observed that the flange formed by the stationary disk 17 which is secured to the top of the post is received between the upper and lower members 22 and 20 which turn with the seat with a retarding frictional resistance, as explained above. With this construction, the seat and the occupant on it are amply supported at the top of the post regardless of whether the weight of the occupant is thrown forward or back against the back rest of the seat and the occupant may turn the seat regardless of his position on the seat and without causing any material wear on the engaging parts.

In addition to the above, I have provided a very effective means for holding the seat in various positions of adjustment and for permitting easy adjustment of the height of the seat. This consists of a dog 23 pivotally supported by a screw 24 between a pair of laterally projecting ears 25^a of a sleeve or collar 25 which is fitted onto the end of the tube 12. The inner edge of this dog engages in a spline groove 13^a of post 13 and this portion of the dog is provided with the equivalent of teeth which are adapted to engage the back wall of the groove, as illustrated in Fig. 2. Furthermore, the groove engaging portion of the dog is somewhat cam-shaped so that by lifting the outer end of the dog, the post 13 will be released from the tube allowing the post to be moved up or down. Furthermore, the dog is so shaped that when it is released, it will swing by gravity into locking engagement with the post so as to grip it, the whole being so constructed that the weight of the seat and of the occupant on it has a tendency to increase the gripping engagement between the dog and post so as to prevent accidental or unintentional lowering of the seat.

A similar dog is preferably provided for holding the post, which supports the desk 11, 45 at any desired height in the other end of the tube 12.

Having thus described my invention, I claim:

1. In a swivelled seat or chair construction, 50 a seat, a supporting post having at the top a circularly corrugated flange, and a plate secured to the lower side of the seat and having an offset portion extending beneath said flange. 55

2. In a swivelled seat or chair construction, a seat, a supporting post having at the top a circularly corrugated flange, a plate secured to the lower side of the seat and having an offset portion extending beneath said flange, 60 and a wear resisting plate between the seat and said flange and top of the post.

3. In a swivelled seat or chair construction, a seat, a supporting post having at the top a laterally projecting flange, a plate having an 65 offset portion and extending under the flange, and a bowed wear resisting plate lying within the offset portion of said first-mentioned plate between the seat and the flange and top of the post. 70

4. In a swivelled seat or chair construction, a seat, a supporting post having at the top a supporting flange which is corrugated and has peripheral lugs, a plate secured to the lower side of the seat and having an offset portion extending under said flange, said plate having a stop shoulder adapted to be engaged by two of said lugs to limit the swivelling movement of the seat, and a free wear resisting disk in said offset portion of 80 the plate engaging the underside of the seat and also the top of the post and the flange. 75

In testimony whereof, I hereunto affix my signature.

CLARENCE E. STEVENS.
